JET PUMP

Rufus Joel Matthews, Nashville, Tenn.

Application April 20, 1943, Serial No. 483,778

2 Claims. (Cl. 103—260)

This invention relates to new and useful improvements in deep well pumps and more particularly to a pump of the jet type.

The principal object of the present invention is to provide a jet type deep well pump constructed in such a manner as to prevent accumulation of foreign matter in the nozzle, which is the principal fault with the present-day jet pumps.

Another important object of the invention is to provide a sump for jet type pumps into which foreign matter can precipitate and remain over long periods of time without interfering with the jet nozzle.

Other objects and advantages of the invention will become apparent to the reader of the following description.

In the drawing:

Figure 1 is a fragmentary vertical sectional view through the jet portion of the pump.

Figure 2 is a fragmentary sectional view taken on the line 2—2 of Figure 1.

Figure 3 is a cross section on the line 3—3 of Figure 1.

Figure 4 is a section on the line 4—4 of Figure 1.

Figure 5 is a section on the line 5—5 of Figure 1.

Figure 6 is a section on the line 6—6 of Figure 1.

Figure 7 is a section on the line 7—7 of Figure 1.

Figure 8 is a section on the line 8—8 of Figure 1.

Figure 9 is a section on the line 9—9 of Figure 1.

Referring to the drawing wherein like numerals designate like parts, it can be seen that numeral 5 denotes a pressure pipe which extends downwardly from the usual pumping apparatus (not shown) to a fitting 6. Numeral 7 denotes an eduction pipe which extends upwardly in substantial parallel relation to the pipe 5 from the upper portion of the fitting 6. In line with the pipe 7 and depending from the fitting 6 is a foot valve 8 and a strainer 9. Adjacent the valve 8 and depending from the fitting 6 in line with the pipe 5 is a sump in the form of a pipe section 10 having a cap 11 at its lower end, this sump forming part of the present invention.

Numeral 12 denotes the usual flared tube projecting into the eduction pipe 7 and which has a throat 13 into which liquid is projected from a nozzle 14. This nozzle 14 is threadedly disposed into the upper portion of a substantially narrow wing formation 15 which projects from the partition wall 16 between the side from which

the sump 10 depends and the side from which the valve 8 depends. This wing formation 15 has a very narrow entrance slot 16. This slot is elongated to take care of volume but very narrow to exclude foreign matter. This slot is the entrance to a canal 17 which gradually constricts but widens in dimension as is clearly depicted in Figures 4 to 9, inclusive, until the jet nozzle 14 is reached.

10 It can now be seen, that the main points of the present invention are the sump 10 for catching foreign matter that is unable to enter the canal 17 due to the nearness of the slot 16 and that the said slot 16 is no wider than the orifice in the jet nozzle 14 so that if any very small particles pass into the canal 17, they must be small enough to also pass through the nozzle 14.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A jet unit for jet pump systems comprising a fitting having a pressure line extending to the upper portion thereof, a sump underlying the fitting at the pressure pipe, an eduction pipe rising from the fitting, a foot valve on the fitting underlying the eduction pipe, a jet nozzle underlying the eduction pipe, said valve and eduction pipe being in communication, and a canal extending from the jet nozzle to the pressure side of the fitting and having its entrance overlying the sump, the pressure entrance of said canal being in the form of an elongated slit, said canal pressure entrance reducing in transverse dimension toward the jet.

2. A jet unit for jet pump systems comprising a fitting having a pressure line extending to the upper portion thereof, a sump underlying the fitting at the pressure pipe, an eduction pipe rising from the fitting, a foot valve on the fitting underlying the eduction pipe, a jet nozzle underlying the eduction pipe, said valve and eduction pipe being in communication, and a canal extending from the jet nozzle to the pressure side of the fitting and having its entrance overlying the sump, the pressure entrance of said canal being in the form of an elongated slit, said canal pressure entrance reducing in transverse dimension toward the jet, said entrance slit being substantially narrower than the orifice of the jet nozzle.

RUFUS JOEL MATTHEWS,
